UNITED STATES PATENT OFFICE.

HENRY L. BRUEN, OF EAST ORANGE, NEW JERSEY.

DESIGN FOR A NOZZLE FOR SYRINGES.

59,952.

Specification for Design.

Patented Dec. 13, 1921.

Application filed July 14, 1921. Serial No. 484,776. Term of patent 14 years.

To all whom it may concern:

Be it known that I, HENRY L. BRUEN, a citizen of the United States, residing at East Orange, county of Essex, State of New Jersey, have invented a new, original, and ornamental Design for a Nozzle for Syringes, of which the following is a specification, reference being had to the accompanying drawing, forming part thereof, wherein,—

Figure 1 is a side elevation; and Fig. 2 a cross sectional view of the nozzle for syringes, showing my new design.

I claim:

The ornamental design for a nozzle for syringes, as shown.

HENRY L. BRUEN.
